S. B. BRITTON,
SAFETY GAS VALVE.
APPLICATION FILED OCT. 15, 1918.

Patented May 6, 1919.

WITNESS:

Wm. Driscoll

INVENTOR,
Samuel B. Britton,
BY
John M. Stewart,
ATTORNEY

UNITED STATES PATENT OFFICE.

SAMUEL B. BRITTON, OF PATERSON, NEW JERSEY.

SAFETY GAS-VALVE.

1,303,156.

Specification of Letters Patent.

Patented May 6, 1919.

Application filed October 12, 1912. Serial No. 259,002.

To all whom it may concern:

Be it known that I, SAMUEL B. BRITTON, a citizen of the United States, residing at Paterson, in the county of Passaic and State of New Jersey, have invented certain new and useful Improvements in Safety Gas-Valves, of which the following is a specification.

My invention relates to safety gas valves, and it consists in a safety gas valve having a key adapted on turning it and with it the valve-proper to a predetermined position, as the closed position, to interlock with the casing of the gas valve, the same being characterized among other advantageous features by the valve-proper and key being in effect a unitary body and so constructed that the valve-proper of any ordinary gas valve may be removed and my valve-proper and key substituted without further change in the gas valve than the provision of a notch in its casing to afford the desired interlock.

In the drawing,

Figure 1 is a side elevation of a gas valve constructed in accordance with my invention, the valve-proper being in the open position;

Fig. 2 is a vertical longitudinal sectional view of the casing, the valve-proper and key appearing partly in side elevation and partly in vertical section and turned to the closed position;

Fig. 3 shows the valve-proper and key and a part of the casing mainly in vertical section, the valve-proper being in closed position, and the section being longitudinal of the valve casing;

Fig. 4 shows the valve-proper and key and a part of the casing mainly in vertical section, the valve-proper being in the closed position, and the section being here transverse of the valve casing;

Fig. 5 shows a side elevation and underneath plan of the valve-proper; and

Fig. 6 is a view similar to Fig. 3 but showing a modification.

a designates the valve casing of an ordinary gas valve, *b* being its gas passage and *c* the conical bore, intersecting said passage, for the valve-proper. The boss *d*, which is usually provided with a quadrant notch to receive the stop pin on the valve-proper in ordinary gas valves, is in the present case formed plain excepting for two diametrically opposite notches *e*.

f is the valve-proper received in and

formed conical to fit the bore *c*. To retain it in place there are provided the usual washer *g* and screw *h* which are attached to its smaller end and bear against the valve *c* casing. It has a transverse port *i* to register with the passage *b* of the valve casing. It is further formed in its larger end portion with a cylindrical chamber *j* and has an interior flange *k* at the outer or lower end *l* of said chamber; extending from its lower or larger end longitudinally of and in the valve-proper there is, further, a slot *l*. The slot extends so far into the valve-proper that when the latter is assembled with the casing it will reach above a bearing surface *m* which the boss *d* affords around the valve-proper excepting where the notches *e* exist. Preferably, the valve-proper is formed with an axial counter-bore *n* opening into the chamber *j* and forming a bearing.

The key consists of the key proper or handle *p* having a spindle *o* and a cross-pin *p* driven into the transverse hole *q* in the spindle. The spindle in the assembled condition *o* of the parts has a bearing at its free end in the counterbore *m*, and also in the flange *k*.

Interposed between the flange *k* and the cross-pin *p* and serving to press the key upwardly or toward the casing is a spiral *r* spring housed in the chamber *j* around the spindle.

The valve-proper, key and spring may be assembled by first introducing the spring into the chamber *j* (which may be accomplished by screwing it into the reduced entrance therein afforded by the flange *k*), then introducing the spindle with its cross-pin *p* removed, and finally driving the cross-pin into place in its hole *q* and over the spring, preferably upon having first turned the key so that the hole registers with the notches *e*.

In the modified form shown in Fig. 6 all the parts are substantially the same as in Figs. 1 to 5 excepting that the flange *k* is omitted and one or more pins *s* are driven into the larger end of the valve-proper to form the abutment for the spring.

The operation of the device will be apparent. The spring presses the key upwardly, holding the cross-pin against the casing. If the cross-pin registers with the notches *e* it will enter the same and therewith form an interlock against turning the key. If now the key be pulled against the tension of the spring so that the cross-pin clears the

notches, the key may be turned so as to permit the cross-pin to impinge against the bearing surface d' .

Having thus fully described my invention, what I claim as new and desire to secure by Letters Patent is:—

In combination, a valve casing having a passage to be controlled, a valve journaled in the casing and having a port movable into and out of registry with the passage, said casing having a notched bearing surface extending around the axis of the valve-proper and said valve being held against move-

ment in the casing longitudinally of its axis, a key movable in the valve and having a laterally projecting part, the valve having a chamber around the key and a longitudinal slot opening into said chamber and through which said part protrudes, and a spring in the chamber interposed between said part and a portion of the valve and holding said part against said surface, said part being enterable into the notch of said surface on turning the valve.

In testimony whereof I affix my signature.

SAMUEL B. BRITTON.
